His Attorney.

UNITED STATES PATENT OFFICE

2,616,135

FASTENING DEVICE

Harold C. Holden, Syracuse, N. Y., assignor to
 General Electric Company, a corporation of
 New York

Application December 29, 1949, Serial No. 135,680

3 Claims. (Cl. 20—92.4)

1

My invention relates to fastening devices and, more particularly, to unitary fastening devices adapted securely to hold complementary members in abutting relationship.

In certain instances, it is necessary to hold a plurality of members such as panels or the like in interfitting relationship with a minimum of frontal area occupied by the fastening means. Such a requirement, for example, arises in certain cabinet structures wherein a metal panel forming the front face of the cabinet is to be fastened to the main body of the cabinet, but because of space limitations determined by the styling of the cabinet it is impractical to use conventional fastening means such as self-tapping screws, snap fasteners and the like. Accordingly, it is a primary object of my invention to provide a fastening device for clamping together a pair of members wherein a minimum of frontal area is occupied by such device.

It is a further object of my invention to provide a new and improved fastening device adapted to fasten together two complementary members which may be quickly and easily assembled.

It is another object of my invention to provide a new and improved fastening device which is suitable for holding a front panel to the main body of a cabinet which is of simple construction and is of low cost.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing, in which Fig. 1 is a perspective view of a cabinet structure employing my improved fastening device; Fig. 2 is a perspective view of the fastening device, per se; Fig. 3 is a top view of the structure of Fig. 1; Fig. 4 is a side elevational view of the structure of Fig. 1 showing the method of insertion of the fastener; Fig. 5 is an elevational view of Fig. 1 showing the method of removal of the fastener; Fig. 6 is a perspective view of an alternative form of the fastener of Fig. 2; and Fig. 7 illustrates the alternative device of Fig. 6, embodied in a cabinet structure.

Referring now more particularly to the drawing, the unitary fastening device 1 is shown therein as clamping a front panel 2, which is shown in fragmentary form to a supporting member 3, also shown in fragmentary form. The

2

support member 3, which may be of any suitable material such as plastic, or the like, is provided with an upstanding sill portion 4 against which the lower edge of the panel 2 is pressed through the action of the device 1. The support member 3 is provided with a pair of spaced parallel bosses 5 which are preferably made integral with support 3 and extend away from the sill portion 4 in a direction perpendicular thereto. The adjacent edges of the bosses 5 are provided with undercut portions 6 so that the bosses 5 together with the surface of support 3 form a dovetail groove.

The construction of the unitary fastening device 1 is illustrated more clearly in Fig. 2, wherein it is seen that the device 1 is provided with a flat base portion 10 and a tongue portion 11 which is narrower than the base portion 10 and extends upwardly at an angle "d" from one end of the base portion. A tab 12 is formed in the fastener 1 intermediate the base and tongue portions 10, 11.

When the fastener 1 is in the assembled relation shown in Fig. 1, the tongue portion 11 is pressed against the inside surface of the panel 2 and causes a tilting of the base portion 10 thereof within the dovetail groove. As a result of such tilting action, the shoulders 7 which are intermediate the base portion 10 and tongue portion 11 are urged into wedging engagement with the undercut surfaces 6 so as securely to hold the tongue portion 11 in position. Likewise, due to such tilting action, the lower edge 8 of the base portion 10 is wedged against the surface of the support member 3 so as to provide additional clamping action. The length "b" of the base portion 10 is preferably made sufficiently small that the base portion may tilt by a substantial angle before the shoulders 7 and edge 8 engage the edges of the dovetail groove, thereby increasing the wedging action exerted by the base portion 10.

The width "a" of the base portion 10 of the fastener is made sufficiently great so that the base portion may be slid into the dovetail groove formed in the support member 3. This is well illustrated in Fig. 3 which is a plan view of the fastener and cabinet structure of Fig. 1. Fig. 3 shows the positioning of the base portion 10 with respect to the bosses 5, and it is evident that the end portions of the base 10 slide under the edges of the bosses 5. The width "c" of the tongue portion 11 of the fastener is made somewhat less than the spacing between bosses 5 so that the tongue portion 11 may project through the opening of the dovetail groove formed thereby and

may engage the inside surface of the panel 2, as discussed above.

The fastener 1 may be assembled with and removed from the panel 2 and support member 3 in a manner illustrated in Figs. 4 and 5. Referring to Fig. 4, the base portion 10 of the fastener is first slid within the dovetail groove formed in the support 3 by bosses 5. In such position, the tongue portion 11 of the fastener projects through the opening of the groove at an angle with respect to the base portion 10 thereof. A wide faced tool 15 is then placed in engagement with the underside of the tab 12, and force is exerted in the direction of the arrow 16 to slide the base portion toward the panel 2. Upon the application of such force, the tongue portion 11 is urged into spring engagement with the inside surface of panel 2, and when sufficient force is exerted thereby the pressure on the tool may be removed. When the pressure is removed, the base portion 10 is tilted in the dovetail groove due to the resilient action of tongue 11 which urges the upper and lower edges of the base portion 10 into wedging engagement with the sides of the dovetail groove as has been discussed in connection with Figs. 1 and 2.

The removal of the fastener may be accomplished as is illustrated in Fig. 5, wherein an application tool 17 having a hooked end portion 18 is placed in engagement with the upper surface of the tab 12. Force is then exerted downwardly on the tip 18 in the direction of the arrow 19, and at the same time a pulling force in the direction of the arrow 20 is exerted on the fastener so that the edges of the base portion 10 are freed from the sides of the dovetail groove and the fastener is slid outwardly from panel 2 so as to remove the tensioning force of the tongue portion of the fastener.

Inasmuch as the wedging action is obtained by engagement with the cabinet and without the use of auxiliary speed screws and the like, the unitary fastening device is particularly suitable for use in cabinets of plastic construction. However, it will be understood that a unitary fastening device constructed in accordance with my invention may be equally well employed in other types of cabinets, such as wood, composition and the like.

The fastening device of Fig. 1 may be modified so as to provide proper clamping action in a variety of circumstances. For example, the tongue portion of the fastener may be modified as is illustrated in Fig. 6, wherein the tongue portion 11 is provided with an upstanding portion 25 and a flat portion 26 which is substantially parallel to the base portion 10 of the clip. By such an arrangement, a member 27 which may comprise the edge of a loud speaker or any similar object may be clamped in place as well as held in upright position.

The modified fastener of Fig. 6 may be used to support and clamp various objects within the cabinet in a manner illustrated in Fig. 7, wherein there is shown a side elevational view of a portion of the radio cabinet together with a loud speaker mounted in place by means of the modified fastener of Fig. 6. The base member and front panel of the cabinet have been given the same reference numerals as in Fig. 1, and further reference need not be made thereto in connection with Fig. 7. The top panel 30 of the cabinet is provided with a pair of bosses 31 which are shaped so as to define a dovetail groove in the manner of the bosses 5 of Fig. 1. The front

panel 2 is provided with a shelf 32 on which the lower rim of a loud speaker 33 may rest; the rim of the loud speaker being cushioned in a rubber block 34. The upper edge of the speaker 33 is cushioned in a rubber pad 35 and is held in place by means of a fastener 36 which is shaped similarly to the fastener of Fig. 6. It will be evident that the fastener may be clamped within the cabinet by exerting a forward pressure on the fastener 36 so as to move the base portion thereof forward and exert a spring pressure thereon so as to tilt the base portion 10 within the groove between bosses 31, thereby wedging the same securely within the groove between bosses 31.

While I have illustrated my improved fastener as clamping the loud speaker of a radio apparatus, it will be obvious that the fastener may equally well be employed in many other arrangements in which two members are to be clamped together by applying pressure externally thereof which tends to hold said members in abutting relationship.

While the invention has been described by reference to particular embodiments thereof, it will be understood that numerous modifications may be made by those skilled in the art without departing from the invention. I therefore aim in the appended claims to cover all such equivalent variations as come within the true spirit and scope of my invention.

What I claim as new and desire to secure by Letters Patent of the United States is:

1. A clamped assembly comprising a base member having a transverse sill, a panel member abutting said sill, said base member also having means defining a pair of spaced, opposed walls extending under and away from the abutting surfaces of said panel member and sill in a direction perpendicular thereto, said walls being inclined to each other so as to define a dovetailed groove wider at its bottom than at its top, and a unitary fastening device comprising a flat base portion and a resilient tongue portion inclined at an angle to said base portion, said base portion being positioned within said groove and having a width smaller than the bottom width and greater than the top width of said groove, said tongue portion having a width narrower than the top width of said groove and extending upwardly through the top of the groove, said tongue portion being urged against said panel member and clamping said panel member between said sill and said tongue, and said base portion being tilted within said groove into wedging engagement with the inclined walls of the dovetailed groove.

2. In combination, a base member having a transverse sill, a panel abutting said sill, said base member also including means defining a pair of spaced, opposed walls extending away from said sill in a direction perpendicular thereto, said walls being inclined to each other so as to define a dovetailed groove wider at its bottom than at its top, and a unitary fastening device having a substantially rectangular, flat, base portion positioned within said groove and a resilient tongue portion extending upwardly at an angle to said base portion, the width of said base portion being intermediate the top and bottom widths of said dovetailed groove and the width of said tongue portion being less than the top width of said groove so that said base portion has a pair of sharp corners adjacent said up-

wardly-extending tongue portion, said tongue portion engaging said panel and clamping said panel to said sill, and said base portion being tilted within said groove so as to force said sharp corners into wedging engagement with the inclined walls of said groove.

3. In a cabinet the combination of a base member having a sill, a panel abutting said sill, means defining a dovetailed groove in said base member extending away from said sill in a direction perpendicular thereto, and a unitary fastening device having a flat base portion positioned within said groove and a resilient tongue portion extending upwardly at an angle to said base portion, the width of said base portion being intermediate the top and bottom widths of said dovetailed groove, the width of said tongue portion being less than the top width of said groove so that said tongue portion extends upwardly

therefrom, said tongue portion engaging said panel and clamping said panel to said sill, said base portion being tilted within said groove into wedging engagement with the sides of said groove, said device having an upwardly extending projection intermediate said base portion and said tongue portion to facilitate depressing and moving said device in said groove towards said panel.

HAROLD C. HOLDEN.
